UNITED STATES PATENT OFFICE.

EDWARD TERRY, OF BRIXTON, LONDON, ENGLAND.

ELECTRIC INCANDESCENT LAMP.

1,262,141.

Specification of Letters Patent.

Patented Apr. 9, 1918.

Application filed October 2, 1915. Serial No. 53,742.

To all whom it may concern:

Be it known that I, EDWARD TERRY, a subject of the King of Great Britain, residing at Milton Hall, 117 Loughborough Park, 5 Brixton, London, S. W., England, have invented a new and useful Improvement in Electric Incandescent Lamps, of which the following is a specification.

This invention has reference to electric incandescent lamps of the kind in which the filament supporting pedestal forms part of a detachable stopper or plug adapted for gas tight engagement with the lamp bulb so that when the filament becomes broken or 15 its efficiency impaired the stopper may be separated from the bulb the filament renewed and the parts reassembled.

Numerous attempts have heretofore been made to construct a practicable and serviceable lamp of this kind but all such attempts have failed to produce a commercially successful article chiefly for the reason that where the means for securing a gas tight joint between the lamp bulb and the stopper 25 have been effective great difficulty has been experienced in separating the parts when it is desired to renew the filament the operation being attended with fracture either of the bulb or the stopper or both.

Under the present invention however I have succeeded in producing an incandescent lamp which when exhausted will hold the high vacuum requisite in a lamp of this kind for an indefinite period and in which the 35 parts may be readily separated when repairs are necessary without the danger of breaking or fracture of any part of the lamp.

These ends and such others as may be incidental thereto or as may hereinafter appear are attained by the means which I will now proceed to describe in detail and for a correct understanding thereof reference should be had to the accompanying drawings in which:

45 Figure 1 illustrates in vertical section the upper portion of an incandescent electric lamp embodying my invention and

Fig. 2 represents partly in section and partly in elevation a slightly modified construction.

Referring now to Fig. 1 it will be seen that I provide the bulb *a* with a preferably

slightly tapered neck *b* of sufficient diameter to admit of the filament carried by the stopper being passed therethrough as will 55 hereinafter be described. The neck *b* is formed with a recess *c* on its inner annular wall and is also provided with a circumferential flange *d*. The glass stopper *e* is shaped to fit the neck or mouth *b* of the bulb 60 *a* and is formed with a recess *f* which cooperates with the recess *c* of the neck *b* to form a well *h* for the reception of the sealing medium as hereinafter explained said stopper also having a circumferential flange 65 *g* which when the stopper is in position is spaced apart from the flange *d* on the neck *b* of the bulb to form a cavity in communication with the well *h*.

Formed integrally with the stopper *e* is 70 a depending tubular member *i* to which is fused the filament supporting pedestal *j* said tubular member serving for the reception of the leading in wires *k* the lower ends of which are attached to the usual platinum 75 connections *l* and sealed to form a gas tight joint as is usual in the manufacture of incandescent lamps. Held within the tubular member *i* such as by means of a suitable cement *m* are two metallic tubes *n* the lower 80 ends of which are adapted to receive and make electrical connection with the leading in wires *k*. The opposite ends of the aforesaid tubes *n* are preferably slightly flared to receive and make electrical connection 85 with the leading in wires *o* carried by the cap *p*—to be presently described—adapted for engagement with the standard lamp socket or fitting. An aperture *q* is provided in the wall of the tubular member *i* to which 90 is fused a tube *r* adapted for attachment to a suitable vacuum pump whereby when the parts are assembled as hereinafter explained the bulb *a* may be exhausted.

I will now describe the assemblage of a 95 lamp embodying my invention. The filament *s* having been mounted on the spider *t* the stopper *e* is inserted in the neck *b* of the lamp bulb and a strip of oiled silk *u* or other material wrapped around the edges 100 of the flanges *d*, *g*. A quantity of mercury—which I have found by exhaustive experiments to be the most suitable sealing material—is now introduced into the cavity be-

tween the flanges *d*, *g* and into the well *h* and the bulb is then exhausted through the tube *r* the end of which is sealed when the requisite degree of vacuum is obtained. The 5 metallic cap *p* carrying the leading in wires *o* is now arranged in position care being taken that said wires are inserted in electrical contact in the tubes *n* said cap being secured against rotation in any suitable 10 manner.

When it is necessary for any reason to repair or renew the filament the cap *p* is first detached and the end of the tube *r* unsealed when the stopper *e* may instantly be removed 15 and the filament renewed or repaired and the parts reassembled in the manner above described.

I may in some cases dispense with the tube *r* and exhaust the lamp through the end of 20 the bulb as is commonly done in which case the vacuum can be destroyed when repairs are necessary by drilling a small hole through the "pip" or other part of the bulb and resealing said hole before reëxhausting.

25 In Fig. 2 I have illustrated an additional or precautionary measure for holding the vacuum within the bulb and to this end I provide the stopper *e* with an angularly disposed circumferential groove or channel *w* 30 which is filled with mercury through an aperture *x* in the neck of the bulb the stopper being then partially rotated to interrupt communication between said aperture and groove or channel *w*. Otherwise the construction is similar to that described with 35 reference to Fig. 1.

What I claim is:

1. An incandescent electric lamp comprising in combination a lamp bulb having a 40 neck with an outwardly projecting circumferential flange, a circumferential groove on the inner annular wall of the neck of said bulb, a detachable stopper having an outwardly projecting circumferential flange normally spaced apart from the flange on the 45 bulb and a circumferential groove on the outer annular wall of said stopper registering with the circumferential groove in the bulb neck to form an annular well in communication with the cavity formed by the spacing apart of the bulb and stopper flanges, a sealing medium in said cavity and well, means carried by said stopper for supporting the leading in wires and filament, and 55 means for exhausting the lamp bulb.

2. An incandescent electric lamp comprising in combination a lamp bulb having a neck with an outwardly projecting circumferential flange, a circumferential groove on 60 the inner annular wall of the neck of said bulb, a detachable stopper having an outwardly projecting circumferential flange normally spaced apart from the flange on the bulb and a circumferential groove on the

outer annular wall of said stopper registering with the groove in the bulb neck to form an annular well in communication with the cavity formed by the spacing apart of the bulb and stopper flanges, a sealing medium in said cavity and well, a depending tubular 65 member carried by said stopper, means located in said tubular member for making electrical connection with the leading in wires of the lamp, a filament support secured to said tubular member, a filament, and 70 means for exhausting the lamp bulb.

3. An incandescent electric lamp comprising in combination a lamp bulb having a neck with an outwardly projecting circumferential flange, a circumferential groove extending over the inner annular wall of the neck of the said bulb and the face of the flange thereof, a stopper having an outwardly projecting circumferential flange normally spaced apart from the flange on the 85 bulb and a circumferential groove extending over the outer annular wall of said stopper and the face of the flange thereof and registering with the groove in the bulb neck to form a well in communication with the cavity formed by the spacing apart of the bulb and stopper flanges, a sealing medium consisting of mercury in said cavity and well, a depending tubular member carried by said stopper, tubes located in said tubular member 90 for making electrical connection with the leading in wires of the lamp, a filament support secured to said tubular member, a filament, an aperture in said tubular member, and an exhausting tube in communication 100 with said aperture.

4. An incandescent electric lamp comprising in combination a lamp bulb having a neck with an outwardly projecting circumferential flange, a circumferential groove 105 extending over the inner annular wall of the neck of the said bulb and the face of the flange thereof, a detachable stopper having an outwardly projecting circumferential flange and a circumferential groove extending over the outer annular wall of said stopper and the face of the flange thereof and registering with the groove in the bulb neck to form a well, a sealing medium in said well, means carried by said stopper for supporting the leading in wires and filament, means for exhausting the lamp, a cap to inclose the stopper and said circumferential flanges, said cap carrying leading in wires and being adapted for engagement with the lamp 115 socket or fitting.

5. An incandescent electric lamp comprising in combination a lamp bulb having a neck with an outwardly projecting circumferential flange, a circumferential groove on 120 the inner annular wall of the neck of said bulb, a stopper having an outwardly projecting circumferential flange and a circumfer-

ential groove on the outer annular wall of said stopper registering with the groove in the bulb neck to form a well, an obliquely disposed circumferential groove in said stopper, a sealing medium in said well and groove, means carried by said stopper for supporting the leading in wires and filament,

means for exhausting the lamp, a cap to inclose the stopper and said circumferential flanges, said cap carrying leading in wires 10 and being adapted for engagement with the lamp socket or fitting.

EDWARD TERRY.
